US0D1074629S

(12) **United States Design Patent** (10) **Patent No.:** **US D1,074,629 S**
(45) **Date of Patent:** **** May 13, 2025**

(54) **CURING BOX**

(71) Applicant: **SAINSTORE TECHNOLOGY CO., LTD**, Dongguan (CN)

(72) Inventors: **Yangjian Deng**, Dongguan (CN); **Jiahao Lin**, Dongguan (CN)

(**) Term: **15 Years**

(21) Appl. No.: **29/862,792**

(22) Filed: **Dec. 13, 2022**

(30) **Foreign Application Priority Data**

Jul. 2, 2022 (CN) 202230415772.7

(51) **LOC (15) Cl.** **15-09**

CLAIM

The ornamental design for a curing box as shown and described.

DESCRIPTION

FIG. 1 is a perspective view of a curing box showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the curing box that form no part of the claimed design.

1 Claim, 8 Drawing Sheets
